UNITED STATES PATENT OFFICE.

BENJAMIN R. HESS, OF BUFFALO, NEW YORK.

MATCH CONTAINER.

Application filed October 21, 1922. Serial No. 595,959.

My invention relates to a match container, and it has more particular reference to that type of container which includes a cigar cutter and windshield.

5 The primary object of my invention is the provision of a container of simple construction having applied thereto an improved pivoted member straddling the body portion of the container and adapted to be swung outwardly therefrom to provide a shielded lighting space.

Another object of my invention is to provide a container of this type which in its preferred construction includes novel means 15 for rendering the matches accessible when providing a wind space in which to light a cigarette, cigar, pipe or the like.

Still further objects are to provide a container having a body portion adapted to receive a box of safety matches and having applied to said body portion a novel straddling member pivotally connected to one corner of said body portion and adapted to swing outwardly therefrom to provide a windshield; also to construct the parts of the container that they co-operate in an improved manner to partly project the body portion of the match box from its cover when moving said straddling member outwardly to form a windshield and to cause the body portion of the match box to be drawn into its cover when moving said straddling member into normal position.

With the above and other objects in view 35 to appear hereinafter, the invention consists in the novel features of construction and in the arrangement and combination of parts to be hereinafter described and more particularly pointed out in the subjoined 40 claims.

In the drawings:—

Fig. 1 is a perspective view of my improved match container, the same having a safety match box therein.

45 Fig. 2 is a perspective view of said container with a safety match box therein, showing the straddling member or windshield extended to form a lighting space and showing the body portion of a safety match box partly projected to render the matches therein readily accessible.

50 Fig. 3 is a longitudinal section taken through the container and the safety match box therein, a part of the match box being

broken away to better illustrate certain features of my invention.

Fig. 4 is a similar view showing the parts as represented in Fig. 2.

Fig. 5 is a longitudinal section taken on line 5—5, Fig. 3.

Fig. 6 is a detached perspective view of the straddling member or windshield with its projector tongue, part of one side of said straddling member or windshield being broken away.

Fig. 7 is a transverse section taken on line 7—7, Fig. 3.

Fig. 8 is a sectional perspective view of one end of the body portion of the match box.

In the drawings the numeral 15 designates the body portion of a match box, and 16 the cover for the same. The body portion 15 of the match box is of special construction and is used in connection with the cover of an ordinary safety match box, it being adapted to displace the ordinary body portion of a safety match box and to be formed of tin or some other thin substantial material. One end of said special body portion has a transverse slot 17 formed therein, which is enlarged at one end, as at 18. The body portion of the box 15 may be said to form a part of the container, as it is adapted to be filled with matches taken from time to time from the ordinary safety match boxes. While the cover of a single box from which the matches are taken may be used in connection with the body portion 15 during a number of fillings, a new cover is preferably used with each filling of the body portion, since they would be of no use after removal of matches from the boxes of which they form part. By using a new cover with each filling, two new striking surfaces for the matches are furnished with each filling.

The container comprises a three-sided open ended member 19 and a straddling member or windshield 20, the three-sided member, although so referred to, has two 100 side walls 21, 22 and an edge wall 23 connecting corresponding edges of said side walls. Said three-sided member may for convenience be referred to as the body portion of the container; and more particularly defined, this body portion is open at opposite ends and at one edge, it being of smaller dimension in depth than in width and hav-

ing a spring tongue 24 stamped from one of its sides, said tongue having its free end directed downwardly and being adapted to engage one of the sides of the cover of the 5 match box and hold the same within the container, or more particularly, the body portion of the container.

The edge wall 23 has an elongated opening 25 formed therein through which the 10 prepared or striking surface 26 at one edge of the match box is exposed. The straddling member or windshield of the container comprises an edge wall 27 and two side walls 28, 29, which may be given any desired for- 15 mation, but are preferably parti-circular.

The windshield is adapted to close the open edge of the body portion of the container, and for this reason it is pivotally connected at its lower end to the lower end 20 of said body portion near the free edges of the side walls thereof, as at 30. The container is preferably formed of material having a certain degree of resiliency so that the side or straddling walls of the wind- 25 shield lie in firm contact with the side walls of the body portion of the container.

The edge wall of the windshield is pro- 30 vided with an elongated opening 31, and when swung inwardly against the open end of the body portion of said container said elongated opening exposes an elongated re- 35 gion of the prepared or striking surface 32 at the adjacent edge of the cover of the match box. The side of the body portion 35 of said container opposite that having the tongue 24 is provided with a segmental slot 33 having the pivots 30 as its center, and the corresponding side 28 of the windshield has a teat 34 stamped inwardly therefrom 40 adapted to project into said segmental slot, said teat being adapted to strike the end 35 of said slot when swinging said wind- 45 shield outwardly, thus limiting outward movement of the windshield.

The side wall of the body portion of the container having the tongue 24 stamped therefrom has its free edge beveled inwardly, as at 36, to form a knife or cutting edge near its upper end, and the corresponding side 50 29 of the windshield is provided with an opening 37 adapted to pass said cutting edge when swinging the windshield outwardly or inwardly. It is, of course, to be under- 55 stood that the windshield is to be swung outwardly a sufficient distance to bring the opening 37 beyond the knife or cutting edge, after which the tip of a cigar may be inserted through the opening, and when closing said windshield, said tip will be severed from the 60 body portion of the cigar by said knife or cutting edge 36.

Projecting inwardly from the lower end of the edge wall 27 of said windshield is an 65 actuating tongue 38, which is retained in locked connection with the body portion of

the match box 15, and for this purpose said tongue has a narrow right-angled extension 39 at its outer end provided at its extremity with laterally-projecting lugs 44, the bent portion of said extension being therefore sub- 70 stantially of T-formation and serving as combined pivotal and slidable means of connection between said tongue and the body portion of said box.

In order to connect the tongue with the 75 lower end wall of said box, the widened ex- 80 tremity of said angular extension, or the head of the T-shaped portion thereof as it may be termed, has passed through the en- 85 larged or widened end 18 of the slot 17, 89 said angular extension being then drawn into the narrow or major portion of said slot so that the lugs 44 or the widened portion of 95 said extension lie against the inner sur- 99 face of the end wall of the body portion of the box 15 at opposite sides of said slot 17, thus retaining said tongue in direct connec- 103 tion with said body portion. For the pur- 109 pose of concealing the tongue within the body portion of the container, said body por- 113 tion is slightly longer than the match box 117 inserted thereinto.

Matches removed from the container may be lighted through the elongated opening in the body portion of the container or the wind- 105 shield when it is not found necessary to protect the flame from the wind. However, when lighting a cigar or the like in the open air, especially when the wind is blowing, it is simply necessary to swing the windshield 110 outwardly to bring the teat 34 against the end 35 of the segmental slot 33, which will position the edge wall 27 of said windshield at an acute angle to the adjacent prepared edge wall of the match box cover and form a 115 triangular lighting space 40 between said two edge walls. The distance between the edge wall of the windshield and the adja- 120 cent edge wall of the match box cover will permit a match, illustrated for instance by the 110 dotted lines 41 in Fig. 4, to be passed into the triangular lighting space 40 and against the adjacent prepared edge of the match box cover, and while preparing to strike the 125 match against said prepared edge, a cigar 115 inserted into the large upper open end of the lighting space, as illustrated for instance by the dotted lines 42 in Fig. 4, will be pro- 120 tected from the wind, after which the match may be moved in frictional contact with 125 said prepared edge to cause the match to be lighted. The flame and cigar thus pro- 130 tected against the wind will assure con- 135 venient lighting of the cigar. After the cigar is lighted, the windshield may be 135 swung inwardly against the match box, and when in this condition, the container will be compact and only a trifle larger than the ordinary safety match box with which it is adapted for use, thus permitting the con- 139

tainer to be conveniently placed in a pocket.

It will be clear from the foregoing that the container is formed of two relatively movable parts, and that it is extensible and contractable.

In Fig. 4 it will be seen that the outward swinging movement of the windshield will cause the tongue 38 thereof to project the body portion of the match box from the upper end of the container a sufficient distance to conveniently permit the withdrawal of a match, and that when swinging the windshield against the open edge of the body portion of the container, the body portion of the match box will be drawn back into the container.

Having thus described my invention, what I claim is:—

1. A match container comprising a body portion, a box slideable in said body portion having a slot in one of its end walls enlarged at one of its ends, a windshield pivotally connected to said body portion at one corner thereof and having an inwardly extending tongue provided with oppositely-directed lugs passed through the enlarged end of said slot and lying in contact with the inner side of said end wall to cause said box to be

moved outwardly and inwardly within said body portion when swinging said windshield outwardly and then inwardly.

2. A match container comprising a body portion having a match box therein provided with a slot in one end wall, a windshield pivotally connected to said body portion and having a tongue extending into said body portion with its free end passed through the slot of said box and retained therein.

3. A match container comprising a body portion, a box slideable in said body portion and having a part at one end provided with a slot enlarged at one of its ends, a windshield pivotally connected to said body portion and having a tongue whose free end is passed through said slot and retained therein.

4. A match container comprising a body portion having a match box therein, a windshield pivotally connected to said match box, and a tongue and slot connection between said windshield and said match box whereby said match box is moved outwardly when swinging said windshield in one direction and inwardly when swinging said windshield in the other direction.

In testimony whereof I affix my signature.
BENJAMIN R. HESS.
